a corporation of New Jersey

Application June 10, 1953, Serial No. 25,424

Term of patent 14 years

(Cl. D21—6)

To all whom it may concern:

Be it known that I, Donald Macy, a citizen of the United States of America, residing at Pompton Lakes, Passaic County, New Jersey, have invented a new, original, and ornamental Design for a Combined Window Awning and Ventilator, of which the following is a specification, reference being had to the accompanying drawing, forming a part hereof.

The single figure is a perspective view of a combined window awning and ventilator, showing my new design. The side of the drawing not shown, has substantially the same appearance as the side shown in the single figure.

I claim:

The ornamental design for a combined window awning and ventilator, substantially as shown and described.

DONALD MACY.
